TOWEL HOLDER OR THE LIKE

Genevieve A. O'Connor, Chicago, Ill.

Application March 14, 1955, Serial No. 55,011

Term of patent 14 years

(Cl. D4—3)

The dominant features of the design reside in the portion shown in full lines.

I claim:

The ornamental design for a towel holder or the like, as shown and described.
